METHOD AND APPARATUS FOR WELL OPERATIONS EMPLOYING HYDROGEN PEROXIDE

Paul G. Carpenter, Bartlesville, Okla., assignor to Phillips Petroleum Company, a corporation of Delaware

Application January 4, 1949, Serial No. 69,212

12 Claims. (Cl. 166—1)

1

This invention relates to processes and apparatus for carrying out operations in a well.

A fuel is burned with hydrogen peroxide. In one specific aspect it relates to processes for removing solid material from a portion of a wall of a hole by burning fuel in hydrogen peroxide. In another specific aspect it relates to cutting pipe in a well by a flame produced from fuel and hydrogen peroxide. In another aspect it relates to perforating a hole in a pipe and/or the wall of a well by a single flame. In another specific aspect it relates to drilling a well employing a jet of burning fuel and hydrogen peroxide.

In prior well operations it has been difficult to obtain a concentrated supply of power in the small diameter of the well hole at a greater depth because of the restricted size of the well hole. It also is disadvantageous to have power supplying cables and/or exhaust gas means running down into a restricted hole.

I have found that hydrogen peroxide in concentrated form in combination with a suitable fuel selected from the group consisting of liquid hydrocarbons, pyrocatechols, alkyl pyrocatechols and hydrazine hydrate produces a self-igniting mixture which burns with the liberation of great quantities of energy and when properly proportioned will oxidize and burn other solid objects such as iron or steel or other metal pipes. The amount of energy contained is comparable to the energy in a like weight of nitro glycerin, but while nitro glycerin must release all its energy at once by detonation, I am able to control the release of energy by supplying the concentrated hydrogen peroxide and fuel to each other at controlled rates and I find the energy release depends on the rate at which these materials are supplied.

One object of the present invention is to provide an improved process and apparatus for removing solid material from a portion of a wall of a well.

Another object is to provide an improved process and apparatus for cutting pipe in two in a well.

Another object is to provide an improved process for perforating a pipe in a well.

Another object is to provide an improved process and apparatus for drilling a well.

Another object is to provide means for mixing and controlling the combustion of fuel and concentrated hydrogen peroxide in a well, and useful well processes employing such combustion.

Numerous other objects and advantages will be apparent to those skilled in the art upon reading the accompanying specification, claims and drawings.

2

Figure 1 is a cross sectional view of a well containing apparatus embodying the present invention and illustrates a process embodying the present invention.

Figure 2 is a cross sectional view of a portion of the apparatus shown in Figure 1 taken along the line 2—2 looking in the direction indicated.

Figure 3 is an elevational view of a modified form of apparatus embodying the invention.

Figure 4 is a cross sectional view of a portion of the lowermost part of Figure 3.

Figure 5 is a cross sectional view of a third form of apparatus which may be substituted for the lowermost portions of Figures 1 or 3.

In Figure 1 a well generally designated as 6 consists of a borehole 7 extending into the earth 8, a portion of which is lined with pipe or casing 9. Suspended in hole 7 is a burner apparatus generally designated 11.

Burner apparatus 11 is suspended at the end of a suspension means such as a cable 12, and in the form of apparatus shown in Figure 1. It is preferred to have a swivel connection 13 and 14 to allow rotation of apparatus 11 without winding up the cable 12.

Apparatus 11 comprises an upper tank 16 and a lower tank 17 having separate filling plugs 18 and 19 for filling tanks with fluids. While it is immaterial whether the hydrogen peroxide is in the upper tank and the fuel in the lower tank or vice versa, I have shown tank 16 filled with hydrogen peroxide to dotted line 21. The space in tank 16 above surface 21 of the hydrogen peroxide is preferably filled with an inert gas such as nitrogen or carbon dioxide under high pressure so that the pressure of the gas may be used to eject the hydrogen peroxide when desired. Similarly tank 17 is filled with oil or other fuel 22 up to level 23 and space 24 contains a gas inert to the oil or other fuel under high pressure for expelling the fuel from tank 17 when desired.

The hydrogen peroxide is withdrawn from tank 11 through outlet conduit 26 and flows through this conduit is controlled by a time valve or shut-off valve 27, the opening and closing of which may be controlled by a suitable clock 28. While not essential to the invention it is a decided safety feature to have a check valve 29 in the outlet conduit 26 to prevent the flow of materials back into tank 16.

The fuel from tank 17 is withdrawn in a similar manner through conduit 31 controlled by a time valve 32 operated by a clock 33 and as a safety feature a check valve 34 prevents back flow in conduit 31.

Conduits 31 and 26 are made into concentric

3

conduits 36 and 37, respectively, in order to form a stator for a reaction jet turbine having a rotor 38. The fuel in outer pipe 36 is led into upper spiral passages 39 of rotor 38 while the hydrogen peroxide coming down the inside of inner pipe 37 is led to lower spiral passages 41. For purposes of disassembly and repair, head 38 may be made in several pieces as indicated which may be connected together in any suitable manner but as the specific construction of head 38 is not part of the present invention, no further details of construction are given.

As shown in Figure 2 the jets of fuel 42 emerging through passages 39 in a non-radial direction cause rotation of head 38 in the direction indicated by arrow 43 as is common in reaction jet turbines and the hydrogen peroxide emerging through similar spiral openings 41 also causes rotation of head 38 in the same direction as 43.

When the hydrogen peroxide and the suitable fuel come together, they ignite spontaneously and burn, and in Figure 1 they have burned an annular groove 44 through the wall of pipe 9 and into the ground 8 to such an extent as to sever lower portion 46 of pipe 9 from the main body of the pipe.

If desired this jet can be concentrated in any single direction as shown in Figures 3 and 4. In Figure 3 a modified burning apparatus generally designated as 11' may be oriented in the hole by surveying it in on the end of a rigid pipe or rod line consisting of pipes 47 and 48 connected by couplings 49. To prevent minor amounts of movement when the jet is turned on, and/or to space the jet the desired distance from the wall and to center the device 11', it may be provided with spring arms 51 which act as spacing means to center the device 11' in the center of the well hole.

The jet 52 at the bottom of device 11' will now be discussed with relation to Figure 4 where it is shown in enlarged form. Pipe 53 may be connected either to the hydrogen peroxide tank 16 or the fuel tank 17 and the other pipe 54 is connected to the opposite tank. The liquid coming down pipe 53 passes through nozzle 56 to link and burn with the liquid coming down pipe 54 and pass out the jet orifice 57 as a hot flame capable of burning its way through steel and other metals and other hard materials.

When downward drilling is desired the jet may be directed downwardly as shown in Figure 5 where pipe 58 is connected to the hydrogen peroxide tank or the fuel tank while pipe 59 is connected to the opposite tank. The liquid coming down pipe 58 goes through jet 61 and meeting with the other liquid burns and passes out jet nozzle 62 in the form of a jet of flame.

Operation

In order to obtain efficient operation, the hydrogen peroxide should be concentrated until it is at least 70% by weight hydrogen peroxide and the remainder being water and a decomposition inhibiting agent of the type known to the prior art. However, higher concentrations of hydrogen peroxide are preferred and a concentration of 98% by weight of hydrogen peroxide gives excellent results. While it is preferred to use a self-igniting fuel, a device such as an automatic spark plug could be positioned adjacent the exit 39 to ignite the fuel and hydrogen peroxide. It is preferred to employ a self-igniting fuel selected from the group of hydrocarbons, pyrocatechol, alkyl pyrocatechols and hydrazine.

hydrate, and of the hydrocarbons, a fuel oil of a gas oil grade is preferred although kerosenes, naphthas, gasolines and liquified petroleum gases may be employed. Liquid hydrocarbons are preferred.

In Figure 1 the apparatus 11 is lowered into the well with time clocks 28 and 33 set to give enough time to position the device at the elevation desired. Time clocks 28 and 33 then open valves 27 and 32 and the inert gases above 21 and 23 force the fuel and hydrogen peroxide, respectively, through pipes 31 and 26 and out spiral passages 39 and 41 into space 44 where they meet and spontaneously ignite (or are ignited by a spark plug not shown). The resulting flame burns an annular groove through casing 9 into wall 8 of the well. Obviously if desired any chemist can calculate the proportions of hydrogen peroxide and fuel (depending on the type of fuel) to provide an oxidizing flame in order to burn up steel or aluminum casing or the like.

While valves 27 and 32 have been shown controlled by time clocks 28 and 33, it is obvious that they could be replaced by electric solenoids controlling these valves from the surface of the ground by means of an electrical circuit including a source of electrical power, switch and wires leading to the solenoids. Obviously, valves 27 and 32 could be provided with a mechanical operating linkage having a portion extending adjacent cable 12 to be operated by a go-devil or a piece of pipe threaded on cable 12 and dropped into the well.

Cutting casing 9 at 44 as illustrated in Figure 1 by lowering device 11 below the bottom of casing 46 the surface of well 8 can be cleaned of deposits in the same manner with the flame of fuel and hydrogen peroxide.

If it is desired to make a perforation in casing 9 or the wall 8 which perforation will extend back into the ground a considerable distance for the release of oil into the well for other processes, the apparatus shown in Figure 3 is employed and if desired jet 52 can be positioned and oriented by surveying the suspension means 47 into the well. By supplying an exhaust of hydrogen peroxide, oxidation or spalling can be enhanced and solid materials present combusted in the perforation.

The flame and jet produced by this apparatus is useful in drilling wells in which case the jet is directed downwardly at 62 as shown in Figure 5. This jet impinges on the bottom of the hole 7 and removes material therefrom, thereby deepening the hole.

While I have shown in the drawings and described in the specification a number of processes and means for carrying out these processes, these have been given for purposes of illustration and the invention is not limited thereto but is as defined in the following claims.

Other combustible organic materials, such as methyl, or ethyl alcohol, can be employed as fuel, but are not as good as those fuels enumerated in the claims because their heat of combustion is less.

Having described my invention, I claim:

1. Apparatus for producing a jet of burning hydrogen peroxide and fuel comprising in combination a tank for said hydrogen peroxide, a tank for said fuel, means to position said tanks in a well, means to supply gas pressure to the liquids in said tanks to eject said liquids, outlet means for said tanks leading to adjacent dis-

5

charge conduits comprising a rotatable reaction turbine, check valves in said outlet means preventing back flow therethrough, a shutoff valve in each outlet means, and means to open said shutoff valves comprising clock means set to open the same at a predetermined time.

2. Apparatus for producing a jet of burning hydrogen peroxide and fuel comprising in combination a tank for said hydrogen peroxide, a tank for said fuel, means to position said tanks in a well, means to supply gas pressure to the liquids in said tanks to eject said liquids, outlet means for said tanks leading to adjacent discharge conduits, check valves in said outlet means preventing back flow therethrough, a shutoff valve in each outlet means, and means to open said shutoff valves comprising clock means set to open the same at a predetermined time.

3. Apparatus for producing a jet of burning hydrogen peroxide and fuel comprising in combination a tank for said hydrogen peroxide, a tank for said fuel, means to position said tanks in a well, means to supply gas pressure to the liquids in said tanks to eject said liquids, outlet means for said tanks leading to adjacent discharge conduits, check valves in said outlet means preventing back flow therethrough, a shutoff valve in each outlet means, and means to open said shutoff valves.

4. Apparatus for producing a jet of burning hydrogen peroxide and fuel comprising in combination a tank for said hydrogen peroxide, a tank for said fuel, means to position said tanks in a well, means to eject said liquids, outlet means for said tanks leading to adjacent discharge conduits, check valves in said outlet means preventing back flow therethrough, a shutoff valve in each outlet means, and means to open said shutoff valves.

5. Apparatus for producing a jet of burning hydrogen peroxide and fuel comprising in combination a tank for said hydrogen peroxide, a tank for said fuel, means to position said tanks in a well, means to eject said liquids, outlet means for said tanks leading to adjacent discharge conduits, a shutoff valve in each outlet means, and means to open said shutoff valves.

6. The process of removing solid material from a portion of a wall of a well bore in the earth comprising positioning a supply of at least 70% by weight hydrogen peroxide adjacent the point of said removal in said bore hole, ejecting said hydrogen peroxide from said supply, positioning a supply of a fuel suitable for combustion with hydrogen peroxide selected from the group consisting of liquid hydrocarbons, pyrocatechol, alkyl pyrocatechols, and hydrazine hydrate, adjacent said point, ejecting said fuel from said supply, contacting said hydrogen peroxide and said fuel, combusting the major portion of said fuel and thereby consuming at least a portion of the oxygen released by decomposition of said hydrogen peroxide and directing the resulting mixture in a jet against said solid material to remove the same.

7. The process of removing solid material from a portion of a wall of a well bore in the earth comprising positioning a supply of at least 70% by weight hydrogen peroxide adjacent the point of said removal in said bore hole, ejecting said hydrogen peroxide from said supply, positioning a supply of a fuel suitable for combustion with hydrogen peroxide adjacent said point, ejecting said fuel from said supply, contacting said hydrogen peroxide and said fuel, combusting the major portion of said fuel and thereby consuming at least a portion of the oxygen released by decomposition of said hydrogen peroxide and directing the resulting mixture in a jet against said solid material to remove the same.

6

major portion of said fuel and thereby consuming at least a portion of the oxygen released by decomposition of said hydrogen peroxide, and directing the resulting mixture in a jet against said solid material to remove the same.

8. The process of removing solid material from a portion of a wall of a well bore in the earth comprising positioning a supply of at least 70% by weight hydrogen peroxide adjacent the point of said removal in said bore hole, positioning a supply of a fuel suitable for combustion with hydrogen peroxide adjacent said point, contacting said hydrogen peroxide and said fuel, combusting the major portion of said fuel and thereby consuming at least a portion of the oxygen released by decomposition of said hydrogen peroxide, and directing the resulting mixture against said solid material to remove the same.

9. The process of severing a pipe in a well bore comprising positioning a supply of at least 70% by weight hydrogen peroxide in said bore hole, ejecting said hydrogen peroxide from said supply, positioning a supply of a fuel suitable for combustion with hydrogen peroxide adjacent said point, ejecting said fuel from said supply, contacting said hydrogen peroxide and said fuel, combusting the major portion of said fuel and thereby consuming at least a portion of the oxygen released by decomposition of said hydrogen peroxide, and directing the resulting mixture in a plane normal to the longitudinal axis of said pipe to cut an annular groove through the pipe to sever the same.

10. The process of perforating a pipe in a well bore comprising positioning a supply of at least 70% by weight hydrogen peroxide in said bore hole, ejecting said hydrogen peroxide from said supply, positioning a supply of a fuel suitable for combustion with hydrogen peroxide adjacent said point, ejecting said fuel from said supply, contacting said hydrogen peroxide and said fuel, combusting the major portion of said fuel and thereby consuming at least a portion of the oxygen released by decomposition of said hydrogen peroxide, and directing the resulting mixture in a fixed jet normal to the surface of the pipe at the desired point of perforation to melt and make by jet action a perforation in said pipe at said point.

11. The process of drilling a well bore comprising positioning a supply of at least 70% by weight hydrogen peroxide in said bore hole, ejecting said hydrogen peroxide from said supply, positioning a supply of a fuel suitable for combustion with hydrogen peroxide adjacent said point, ejecting said fuel from said supply, contacting said hydrogen peroxide and said fuel, combusting the major portion of said fuel and thereby consuming at least a portion of the oxygen released by decomposition of said hydrogen peroxide, and directing the resulting mixture in a jet downward against the bottom of said bore hole to flux and deepen the same.

12. The combination of claim 5 in which the discharge conduits comprise a rotatable reaction turbine.
